UNITED STATES PATENT OFFICE.

HERMAN L. MEYER, OF ST. PAUL, MINNESOTA.

FURNACE STRUCTURE.

1,121,569.

Specification of Letters Patent. Patented Dec. 15, 1914.

Application filed February 21, 1913. Serial No. 749,797.

To all whom it may concern:

Be it known that I, HERMAN L. MEYER, a citizen of the United States, residing at St. Paul, in the county of Ramsey and State of Minnesota, have invented a new and useful Improvement in Furnace Structures, of which the following is a specification.

The object of this invention is to provide a furnace structure for boilers, bake ovens and other purposes in which sufficient air heated to the igniting point is introduced whereby substantially complete combustion is produced without entailing any considerable loss in fuel thus reducing the amount of smoke and other objectionable waste products of combustion, and also producing highly efficient and economical results.

It has been proven by experience that air in passing through burning fuel ignites with the more volatile gases, releasing the carbon to pass off in smoke. With my invention waste heat is utilized to heat air to the igniting point which in turn is introduced where it will burn the free carbon released by the fire.

In the accompanying drawings forming part of this specification, Figure 1 is a longitudinal vertical section of the furnace structure of a boiler setting, embodying my invention; Fig. 2 is a plan of Fig. 1; Fig. 3 is a vertical section taken upon the line Y—Y of Fig. 1; Fig. 4 is a perspective view partly in section of a detail illustrating the damper by which the port openings in the bridge wall may be closed or regulated, and Fig. 5 is a plan view of a detail illustrating an alternative construction for admitting air into the furnace structure.

Referring to the drawings 2 and 3 indicate the front and back walls and 4 and 5 the side walls of a furnace structure forming a setting for the horizontal boiler A. 6 indicates the fire door, 7 the grate supported between the side walls and the front wall and bridge wall B, 8 the clean out door in the back wall 3, and 9 the smoke outlet from the smoke drum 10 in the front end of the boiler, all of these parts being arranged in a suitable manner as is customary in the art of furnace structures for steam boilers.

The bridge wall is suitably positioned across the space below the boiler and between the sides of the furnace structure and with the side walls and front wall 2 forms the usual ash pit 11 below the grate. At the back of the bridge wall there is a floor or

wall C sloping back to the rear end of the furnace structure which with the bridge wall and foundation produce a preheating air chamber D, and a reverberatory chamber E communicating with the fire space F above the grate, by a passage G formed by the lower surface of the shell of the boiler and the top of the bridge wall. By this construction draft issuing from the fire on the grate passes over the bridge wall in contact with the lower surface of the boiler shell into the reverberatory chamber E and from the reverberatory chamber it passes up over the rear end of the boiler and continues horizontally through the boiler, up through the smoke drum and out through the outlet 9.

In order to preheat the air which is used for draft purposes upon the fuel on the grate, the bridge wall is formed with a plurality of air ducts 12, and the side walls 4 and 5 are provided with air inlet passages 13 and 14, leading from the front of the furnace structure and passing into the preheating chamber D through the ports 15. The walls 4 and 5 warm the air which is admitted to the fuel on the grate, the chamber D increasing its temperature and thus aiding combustion, it being well known that hot air fed on a fire produces more complete combustion than cold air. The air ducts 12 may be closed or modified in size for regulating the draft by a damper 16, which is adjusted by a draw bar 19 extending through the wall 4 and a handle 20 connected to said draw bar whereby it can be reciprocated.

It is well known that if air heated to proper temperature is caused to commingle with gases and products of combustion issuing from a fire before they are reduced in temperature, that the tendency is to produce complete combustion, greater economy and reduce the amount of smoke to a minimum. To accomplish this result I have found in practice by exposing the air to the action of heat above or adjacent the bridge wall and admitting the air so heated into the reverberatory chamber where it is caused to commingle while in extremely heated condition with the gases and products of combustion from the fire, substantially all of said products of combustion are consumed and converted into heat. The construction by which this result is produced may be in the form of a pipe or tube H, placed on the upper sur-

face of the bridge wall with its ends 21 and 22 bent down and connected with a passage 23, through the bridge wall extending between the two sides 4 and 5 of the furnace structure, said passage 23 being connected with the reverberatory chamber by a plurality of transverse ducts 24. The tube H is thus exposed to the action of the hottest gases from the fire and by means of the 10 perforations 25 in the side of the tube facing the reverberatory chamber the air which has been superheated (to an extremely high temperature) by the tube and the parts with which the tube connects is admitted into the 15 reverberatory chamber where it commingles and readily unites with the gases and products of combustion. The amount of air which is admitted through the superheating tube H into the reverberatory chamber may 20 be regulated by the dampers 26, on the front wall of the furnace structure over the ends of the passages 13 and 14. By this means the air is superheated progressively, first by the walls of the furnace structure, next 25 by the reverberatory chamber, next by the bridge wall and finally by the superheating tube H, the result being that the air is heated to a high degree of temperature and into condition whereby it produces the most economical and best results when it commingles 30 with the gases and products of combustion in the reverberatory chamber. The fact that the reverberatory chamber increases in size from the bridge wall back to the rear of the boiler causes the gases and products of combustion to expand and thoroughly commingle thus mixing the highly heated air from the superheater tube with the gases and products of combustion. The super- 35 heater tube may be made of copper or other suitable material or its surface may be partly or wholly protected by fire clay or other suitable, non fusible material. Its position or the position of its orifices 25 may also be 40 changed so long as the superheated air is admitted to commingle with the hot gases and products of combustion while they are in a highly heated state and not directly over the fire. The space bounded by the top of the 45 bridge wall, the lower surface of the boiler and the side walls 2 of the furnace structure is closed by walls 30 which co-act with the top of the bridge wall in producing a narrow horizontal space or throat through 50 which the draft from the fire passes and in which the superheating tube is placed, the result being that the bridge wall, super- 55 heating tube and air therein are heated to

a high degree of temperature. It is not necessary that the air be admitted into the reverberatory chamber by passing it longitudinally from the front of the furnace to the rear end of said chamber as described. It being obvious that it may be admitted through passages 27 in the side walls, (see 65 Fig. 5) directly entering the chamber from the outside, each of said passages being regulated such as by a damper 28.

In accordance with the patent statutes I have described the principles of operation 70 of my invention together with the apparatus which I now consider to represent the best embodiment thereof but I desire to have it understood that the construction shown is only illustrative and that the invention 75 can be carried out by other means and applied to uses other than those above set forth within the scope of the following claim.

Having described my invention, what I 80 claim as new and desire to protect by Letters Patent is:—

In a furnace structure, a boiler, outside walls forming a fire space below said boiler, a bridge wall across said space, a grate in 85 front of said bridge wall, a pre-heating air chamber back of said bridge wall and forming the lower side of a reverberatory chamber for gases and products of combustion issuing from burning fuel on said grate, 90 said outside walls having longitudinal passages for air into said pre-heating chamber, and said bridge wall having an air super-heating passage extending longitudinally thereof and formed with entry ports from 95 said pre-heating chamber, and a single air superheating pipe placed longitudinally of and above said bridge wall across the direct action of draft issuing from the fire having a free direct passage for air therein, being 100 bent downwardly at both ends and its ends seated in said bridge wall and connected with the superheating passage therein, said pipe being formed with openings in its rearward side above the bridge wall adapted 105 to expel superheated air from within into said reverberatory chamber where it may commingle with the volatile gases and burn the free carbon from the fire.

In testimony whereof, I have signed my 110 name to this specification, in the presence of two subscribing witnesses.

HERMAN L. MEYER.
